UNITED STATES PATENT OFFICE.

EDGAR HITT, OF KATONAH, NEW YORK.

BUCKBOARD.

SPECIFICATION forming part of Letters Patent No. 228,352, dated June 1, 1880.

Application filed April 20, 1880. (No model.)

To all whom it may concern:

Be it known that I, EDGAR HITT, a citizen of the United States, residing at Katonah, Westchester county, New York, have invented 5 new and useful Improvements in Buckboards, of which the following is a specification.

This invention relates to that class of buckboards or buck-wagons which are constructed with curved spring-trusses, which are connected at their opposite ends to loops attached to the under side of the buckboard, and bear against the board proper at or near the center of their length.

My improvements will be fully hereinafter 15 described, and specially pointed out in the claim.

This invention is illustrated in the accompanying drawings, in which—

Figure 1 represents a side view. Fig. 2 is 20 an inverted plan view.

Similar letters indicate corresponding parts.

The letter A designates the board proper, supporting a seat, B, in the usual manner, and C C the axles. D D are spring-trusses 25 combined with the structure according to my invention.

The spring-trusses D D consist of curved flat strips of metal, and they are flexibly attached at their ends to metal strips D' D', which 30 are bolted to the axles, and also to blocks C' C' situated adjacent and parallel to the axles, the trusses being joined to the strips D' D' by links e e.

At the point where the spring-trusses D D bear against the board A the latter is provided 35 with a block, C².

The part of the fore axle to which the metal strips D' D' are connected is the bolster, the axle proper being arranged on a king-bolt.

It will be seen that by the spring-trusses D 40 D the board A is braced or strengthened in an effective manner, while the elasticity of the board is not injuriously affected by that means.

What I claim as new, and desire to secure 45 by Letters Patent, is—

The combination, in a buck-wagon, of the axles C C and the blocks C' C', arranged parallel to the axles a short distance from the inner sides of the same, with the buckboard A, attached to the upper sides of the axles and 50 to the blocks, the metallic straps D' D', rigidly connecting the axles and blocks, and provided with links e e, adjacent to the inner edges of the blocks, and the curved spring-trusses D D, attached to the links at their ends and supporting the buckboard at or near their center, all 55 as herein shown and described.

In testimony whereof I have hereunto set my hand in the presence of two subscribing witnesses.

EDGAR HITT.
